(57) **CLAIM**

The ornamental design for a tire tread sidewall, as shown and described.

DESCRIPTION

FIG. 1 is a front perspective view of a tire with the tire tread sidewall design of the present application;

FIG. 2 is a side view thereof; and,

FIG. 3 is an enlarged front perspective view of FIG. 1, showing a portion thereof.

In the drawings, the dash-dot lines (—•—•—) depict the boundary between claimed and unclaimed matter, and the dashed lines (— — —) depict unclaimed environmental subject matter only; these broken lines form no part of the claimed design.

1 Claim, 3 Drawing Sheets---
